UNITED STATES PATENT OFFICE.

CHARLES T. WESTLAKE, OF ST. LOUIS, MISSOURI, ASSIGNOR TO COMMONWEALTH STEEL COMPANY, OF ST. LOUIS, MISSOURI, A CORPORATION OF NEW JERSEY.

SEPARABLE BODY-BOLSTER.

1,089,450.

Specification of Letters Patent. Patented Mar. 10, 1914.

Application filed May 16, 1913. Serial No. 768,052.

To all whom it may concern:

Be it known that I, CHARLES T. WESTLAKE, a citizen of the United States, residing at the city of St. Louis, State of Missouri, have invented a certain new and useful Improvement in Separable Body-Bolsters, of which the following is a full, clear, and exact description, such as will enable others skilled in the art to which it appertains to make and use the same, reference being had to the accompanying drawings, forming part of this specification, in which—

Figure 1 is a top plan view of a separable body bolster of my improved construction. Fig. 2 is a side elevational view of the bolster seen in Fig. 1 and showing the center sill with which said bolster is combined, in section. Fig. 3 is a vertical section taken approximately on the line 3—3 of Fig. 2 showing the end sill of a car underframe and the draft sills which are positioned between the ends of the center sills and said end sill. Fig. 4 is a cross sectional view taken approximately on the line 4—4 of Fig. 1.

My invention relates to new and useful improvements in separable body bolsters, that is, a body bolster having a portion which can be easily and quickly applied or detached so as to permit the bolster to be readily combined with the center sills and draft sills of a car underframe.

The principal objects of my invention are to construct a simple, inexpensive body bolster, of cast metal, and to form an opening through the central portion of said bolster for the accommodation of the center sills of the underframe; to provide a readily detachable center plate which spans the opening in the bolster, which plate is provided with a center bearing; and further to provide overlapping webs or flanges on the bolster and the detachable plate, which webs or flanges are attached to each other and form a strut between the detachable plate and the upper part of the body bolster whereby the central portion of the latter is materially strengthened and reinforced.

A further object of my invention is to provide a simple, strong and rigid car underframe construction including center sills, body bolster, and draft sills, which construction can be easily assembled, or in the case of repairs, can be easily taken apart.

To the above purposes, my invention con-

sists in certain novel features of construction and arrangement of parts hereinafter more fully described and claimed.

As shown in the drawings, I employ a pair of center sills, each comprising a vertically disposed web plate 10, to the upper and lower edges of which are fixed angles 11, the same being arranged so that their horizontal flanges are outwardly presented. Positioned on top of the center sills thus formed and attached to the horizontal flanges of the upper pair of angles 11 is a cover plate 12. The web plates 10 of the center sills are provided in their end portions with longitudinally disposed slots 13 which are for the accommodation of the top flange of the body bolster. This body bolster is preferably cast in a single piece and comprises a vertically disposed web 14, a top flange 15, and a bottom flange 16. Thus said bolster is substantially of I beam shape in cross section. The central portion of the body bolster is preferably depressed with respect to its ends and the central portion of the top flange which is preferably reinforced with longitudinally disposed ribs 15 occupies the inner ends of the slots 13. The length of these slots is approximately twice the width of the top flange 15 so that when the body bolster is properly assembled with the center sills the ends of the latter project a short distance beyond the body bolster.

An opening 17 is formed at the center of the body bolster, which opening accommodates the lower portions of the center sills and a removable plate, hereinafter more fully described, and formed on the edges of the webs 14 adjacent to this opening are reinforcing ribs or flanges 18. Formed integral with the top flange 15 of the body bolster near one edge thereof extending downward into the opening 17 is a vertically disposed web plate 19.

The separable portion of the body bolster which spans the space between the ends of the bottom flange 16 at the sides of the opening comprise a plate 20, preferably of cast metal, the ends of which occupy suitable seats or recesses 21 formed in the undersides of the bottom flange 16. This plate is detachably fixed to the bottom plate by means of suitable fastening devices, such as bolts or rivets 22, and formed integral with the underside of said plate is a center bearing 20 which is adapted to engage a correspond-

ing center bearing on the truck bolster. When this plate is properly applied to the bolster, it bears directly against the horizontally disposed flanges of the lower pairs of angles 11 and against the lower edges of the web plates 10.

Formed integral with the plate 20 near one side thereof is an upwardly projecting web plate 23, which, when the plate 20 is 10 properly positioned on the bolster, lies immediately against the depending web plate 19. These two web plates are fixed to each other in any suitable manner, preferably by means of rivets, and thus a strong vertically 15 disposed strut is formed between the detachable plate 20 and the top flange 15 of the bolster. This strut formed by the plates 19 and 23 lies wholly between the web plates 10 of the center sills. Formed integral with 20 the ends of the web plate 23 and with the plate 20 are web plates or flanges 24 which are arranged substantially at right angles to said plate 23 and these plates 24 are positioned against the inner faces of the web 25 plate 10 and being fixed thereto in any suitable manner, preferably by means of rivets.

When the bolster is properly combined with the center sills, the top flange 15 occupies the rear portion of the slot 13 and thus the end portions of the center sills project beyond the bolster. Fixed to these projecting ends, preferably by means of rivets, are the rear ends of draft sills 25 which are preferably channel shaped in cross section with their flanges outwardly presented, and the rear ends of these draft sills bear directly against the front edge of the top flange 15. The outer ends of these draft sills are attached in any suitable manner to the end sill 26 of the underframe. By depressing the central portion of the body bolster the tops of the side sills 27 of the car underframe to which the ends of the bolster are fixed occupy approximately the same horizontal plane with the top plate 12 that is attached to the center sills. The body bolster is preferably formed with integral side bearing members 28 and with projecting plates 29 50 to receive nailing strips.

In combining my improved body bolster with a car underframe, said bolster is positioned with the central portion of the top flange 15 in the rear portions of the slots 13, after which the plate 20 is applied to the underside of the bolster beneath the center sills. The bolts or rivets 22 are now applied through suitable apertures in the ends of the plate 20 and the bottom flange 14 after 60 which the rivets or fastening devices are applied through suitable apertures in the web plates 19 and 23. The web plates 24 are attached to the center sills by suitable fastening devices, such as rivets, and the rear ends 65 of the draft sills 25 are attached to the ends

of the center sills which project beyond the body bolster.

By slotting the center sills to accommodate a portion of the body bolster and making a part of said body bolster separable and removable, said bolster can be very easily and quickly applied to the center sills, when the car underframe is assembled, or in case of repairs, it will be a comparatively easy matter to remove the body bolster from the center sills. The strut formed by the attached web plates 19 and 23 materially strengthens the central portion of the bolster and such construction also serves to firmly unite the separable or detachable plate with the main body 75 portion of the bolster.

It will be readily understood that minor changes in the size, form and construction of the various parts in my improved bolster may be made and substituted for those herein shown and described without departing from the spirit of my invention, the scope of which is set forth in the appended claims.

I claim:

1. In car construction, the combination with center sills provided in their ends with slots, of a body bolster attached to said center sills, a portion of which body bolster occupies said slots, a center bearing plate detachably applied to the bolster beneath the center sills, and a pair of overlapping plates on said bolster and center bearing plate between the center sills, which overlapping plates are connected to form a strut.

2. In car construction, the combination with slotted center sills, of a body bolster having an opening through which parts of the center sills project, parts of which bolster occupy the slots in the center sills so that the latter project entirely through said bolster, a separable center bearing plate attached to the bolster and spanning the lower portion of the opening therein, a web plate integral with said center bearing plate, and a web plate integral with the upper portion of the bolster, which web plates are attached to each other to form a strut between the center bearing plate and the upper portion of the bolster.

3. The herein described body bolster having a single opening near its center adapted to receive parts of sills, which are slotted so that the end portions of the sills project entirely through said bolster, a separable center bearing plate applied to the bolster and spanning the opening therein, and a strut between said center bearing plate and the upper portion of the bolster.

4. The herein described body bolster having an opening near its center adapted to receive parts of sills having slotted end portions which engage with and project entirely through the opening in the bolster, a separable center bearing plate applied 130

to the bolster and spanning the opening therein, and a strut between said center bearing plate and the upper portion of the bolster, which strut is formed by overlapping connected web plates which are integral with the center bearing plate and the bolster.

5. The herein described body bolster provided with an opening adapted to receive parts of sills having slotted end portions which engage with and project entirely through the opening in the bolster, a web plate depending from the upper portion of said bolster within the opening, a separable center bearing plate applied to the bolster beneath the opening therein, and a web plate integral with said center bearing plate, which last mentioned web plate extends upwardly into the opening in the bolster and is fixed to the depending web plate on the bolster to form a strut.

6. In car construction, the combination with center sills having slotted end portions, of a body bolster a portion of which occupies the slots in the center sills, said

bolster having an opening through which parts of the center sills project, a separable center bearing plate applied to the body bolster beneath the openings therein, and a strut member integral with said plate between the center sills.

7. In car construction, the combination with center sills having slotted end portions, of a body bolster a portion of which occupies the slots in the center sills, said bolster having an opening through which parts of the center sills project, a separable center bearing plate applied to the body bolster beneath the openings therein, and strut members integral with said plate and bolster between the center sills, which strut members are attached to each other.

In testimony whereof I hereunto affix my signature in the presence of two witnesses, this 6th day of May, 1913.

CHARLES T. WESTLAKE.
